TELEPHONE SYSTEM

Roswell Harry Herrick, Oak Park, Ill., assignor to
 Associated Electric Laboratories, Inc., Chicago,
 Ill., a corporation of Delaware

Application May 21, 1938, Serial No. 209,197

18 Claims. (Cl. 179—27)

The present invention relates to telephone systems and more particularly to improved telephone apparatus for providing simplified and more direct calling facilities between the telephone substation of an important executive or official and the telephone substations of subordinates who are frequently called from the executive telephone substation.

In applicant's copending application, Serial No. 207,433, filed May 12, 1938, there is disclosed an improved telephone system which is so arranged that the delay incident to the operation of a manual system or the labor incident to the operation of the calling device in automatic systems is obviated. This system is so arranged that calls to a number of telephones may be initiated at the special substation either by using a conventional dial operated calling device or by the simple expedient of selectively actuating calling keys individually corresponding to the telephones which are frequently called. The disclosed arrangement is particularly adapted to be used in conjunction with a private automatic exchange of the type frequently used to provide telephone facilities for the employees of a large manufacturing organization or a large office. More particularly, the apparatus is arranged in an improved manner such that two calls may be simultaneously handled at the special or executive substation forming a part of the system, and auxiliary transmitting means and auxiliary receiving means, including an amplifier and a loud speaker, may be used in lieu of the regular substation transmitter and receiver in communicating over either of two established connections without releasing either of the two connections.

It is an object of the present invention to provide an automatic telephone system wherein two sets of improved and exceedingly simple switching apparatus are utilized for routing connections to and from a special substation, and wherein arrangement of the apparatus is such that connections can only be established between the special substation and the other substations of the system.

It is a further object of the invention to provide improved and exceedingly simple switching apparatus for routing connections from calling ones of a plurality of associated lines to a special substation.

In the illustrated embodiment of the invention there are shown a special or executive substation, a plurality of substation lines and means comprising automatic switching equipment controllable only from the special substation for es-

tablishing connections between said substation and said lines on calls initiated at said substation. More particularly, there is provided in association with the special substation, a plurality of key operated calling switches which individually correspond to the substation lines, an automatic switch, and control means operative in response to the operation of any one of the calling switches for causing the automatic switch to select the called line corresponding to the operated calling switch. Calls incoming to the special substation are routed by way of a branch path common to the lines and including a link line through the operation of auxiliary switching apparatus which is so connected and arranged that connections can only be routed by way thereof to the special substation. This auxiliary switching apparatus comprises line and control relays individually associated with the substation lines and a control relay common to the lines. Each of the control relays includes contacts for connecting the associated substation line to the link line mentioned above and is operative in response to the operation of the associated line relay to complete the operating circuit for the common control relay. Each line relay includes a primary operating circuit arranged to be completed when a direct current bridge is connected across the line conductors of the associated line and a secondary operating circuit arranged to be completed in response to the operation of the common control relay. The common control relay is also operative to cause the operation of a signal device provided at the special substation, thereby to announce incoming calls to this substation.

Further features of the invention pertain to the particular arrangement of the apparatus whereby the above and additional operating features are attained.

The novel features believed to be characteristic of the invention are set forth with particularity in the appended claims. The invention, both as to its organization and method of operation, together with further objects and advantages thereof, will best be understood by reference to the specification, taken in connection with the accompanying drawings, in which Figures 1 to 7, inclusive, taken together, illustrate a telephone system having incorporated therein the above-outlined features of the present invention and Fig. 8 is a diagram illustrating the manner of assembling the other figures of the drawings.

Referring now more particularly to Figs. 1 to 7 of the drawings, there is illustrated a telephone system which may be used to provide exclusive

telephone facilities between certain of the offices of a large office or a manufacturing organization. In brief, the system comprises a special or executive substation including the apparatus shown in Fig. 1 which is arranged to be connected to any one of a plurality of substation lines, two of which are indicated at 701 and 702. The lines of the system terminate in the bank contacts of a line selecting switch 310 and also in auxiliary switching apparatus indicated generally at 700 and including the relay equipment shown in Fig. 7. The lines extend to substations of the manual type, that associated with the line 701 being diagrammatically illustrated at A and that associated with the line 702 being indicated at B. The apparatus provided at each of the substations A, B, etc., may be of any desired commercial construction and arrangement. In brief, this apparatus may comprise the usual hand set type of transmitter and receiver, a cradle or hook comprising supporting means for the receiver, a cradle or hook switch and a ringer or signal device. Preferably, the elements of each substation circuit are connected and arranged to form the well-known anti-side-tone circuit, whereby operation of the substation transmitter does not cause operation of the substation receiver.

For the purpose of routing calls from the executive substation including the apparatus shown in Fig. 1 directly to other lines of the system, there is provided automatic switching equipment comprising the above-mentioned rotary switch 310. This switch is a standard twenty-five point rotary switch and comprises four sets of bank contacts 311 to 314, inclusive, wipers 315 to 318, inclusive, respectively associated with the enumerated contact sets, and means comprising a motor magnet 319 for driving the enumerated wipers over the contacts of their respective associated sets. As indicated, the contacts in the two sets 313 and 314 terminate the line conductors of the respective substation lines, and the contacts in the set 312 terminate the private or control conductors of the lines. The contacts of the fourth contact set 311 terminate conductors extending by way of the cable 295 to the contact springs of a group of coding relays shown in Fig. 2. These conductors individually correspond to the substation lines and are included in marking circuits by means of which operation of the switch 310 is controlled. Since the control apparatus described hereinafter is only arranged to provide facilities for calling twenty substation lines, only twenty of the contacts of each contact set embodied in the switch 310 are used, the remaining contacts being left blank. The switch 310 is arranged to be controlled by the group of coding relays shown in Fig. 2 and by the control apparatus 415 illustrated in Figs. 4 and 5. More particularly, the coding relays shown in Fig. 2 and indicated at R200, R210, R220, R230, R240, R250 and R260, respectively, are arranged to be energized in combinations of three in response to the selective operation of any one of the plurality of calling switches illustrated in Fig. 1. These switches, which are indicated at 100 to 109, respectively, individually correspond to the lines terminating in the bank contacts of the switch 310. Each of the enumerated calling switches is of the key operated type and is operable from a normal position to either of two off-normal positions individually corresponding to two substation lines. Each of the switches is of the well-known locking type, such that, when once operated to an off-normal position, it re-

mains in its operated position until manually restored to normal. The contact springs of the calling switches are wired in the manner illustrated so that, when any one thereof is operated to one of its two off-normal positions, three of the coding relays shown in Fig. 2 are caused to operate in the manner described in detail hereinafter to complete one of the above-mentioned marking paths extending to one of the contacts in the set 311 of the rotary switch 310, thereby to identify the called line desired by the calling party.

The line wipers 317 and 318 of the rotary switch 310 are arranged to be connected by way of a link line comprising the conductors C335 and C339 to a repeating transformer 500 through operation of the control apparatus indicated generally at 415. This apparatus comprises a start relay R456 which is arranged to be energized in response to any one of the calling switches shown in Fig. 1 and functions to initiate the operation of the rotary switch 310 to select a desired called line. Operation of the rotary switch is controlled by the three relays R420, R430 and R440, of which the relays R430 and R440 directly control the stepping operation of the switch 310 and the relay R420 is a test relay for arresting the operation of the rotary switch when its wipers are operated to a position corresponding to a desired called line. The apparatus 415 also includes a ring cutoff relay R550 under the control of a slow-to-operate relay R400, and a back bridge or called party answer relay R510.

As indicated above, the switch 310 and the control apparatus 415 associated therewith are controllable only from the executive substation to route connections to the various substation lines terminating at the switch 310. For the purpose of extending connections to the executive substation on calls originating at the various other substations, the auxiliary switching apparatus 700 is provided. In brief, this apparatus comprises line relays R710, R720, etc., individually associated with the substation lines 701, 702, etc., control relays R730, R740, etc., individually associated with the substation lines and with the line relays; and a pair of common control relays R760 and R790. Each of the control relays R730, R740, etc., includes contacts for connecting the associated line to a link line 780 including line conductors C781 and C782, respectively, extending to the terminals of one side of a repeating transformer 770. The other side of the repeating transformer 770 is arranged to be connected by way of a line 785 comprising the conductors C786 and C787 to one side of a repeating transformer 300, and the other side of the last-mentioned transformer is, in turn, arranged to be connected by way of a link line comprising the conductors C296 and C297 to the substation apparatus provided at the executive substation. As explained in detail hereinafter, the link line 780, the repeating transformer 770, the line 785, the repeating transformer 300, and the link line C296, C297, constitute a branch path by way of which connections are extended to the executive substation on calls originating at the other substations. For the purpose of completing a talking loop including this branch path, there is also included in the auxiliary switching apparatus 700, a slow-to-operate called-party-answer relay R750. This latter relay also functions as a ring cut-off relay.

The two sets of switching and control apparatus, namely, the apparatus 700 and the appa-

ratus 415 have associated therewith ringing apparatus, not shown, which may be of any conventional arrangement. This ringing apparatus is arranged to be started into operation in response to the application of ground potential to the ringing apparatus start conductor C408 and, during operation, the alternating output voltage thereof is impressed between the ringing current conductor C405 and ground in the usual manner. 5 Any desired source of direct current having the proper voltage may be used for energizing the various relays and other circuit elements.

Transmitting and receiving means are provided at the executive substation for use in communicating over connections established between this substation and other substations of the system. Calls incoming to this substation are announced through the operation of an alternating current signal device 168. The transmitting means comprises a microphone 135, and the receiving means comprises a sound reproducing device in the form of a loud speaker, diagrammatically illustrated at 136, connected in tandem with a signal amplifier including the vacuum tube 620. The transmitting and receiving means are interconnected with an anti-side-tone impedance network indicated generally at 630 to form a substation circuit of the well-known anti-side-tone type having line terminals 643 and 644 arranged to be connected by way of a link line including the conductors C575 and C576 to one winding of the repeating transformer 500 or by way of the link line comprising the conductors C296 and C297 to one winding of the repeating transformer 300. More particularly, the anti-side-tone impedance network 630 comprises an induction coil or transformer 618 including five windings 611 to 615, inclusive, the last-mentioned of which is coupled to the primary winding 616 of an input transformer 618 having its secondary winding 617 connected across the non-adjustable terminals of a voltage dividing resistor 619. The adjustable terminals of the resistor 619 are coupled to the control grid 621 and the cathode 622 of the tube 45 620. The tube 620, which is of the well-known pentode type and includes a directly heated cathode, is provided with an output circuit comprising the primary winding 628 of an output transformer 627 connected in series with a source 50 of anode potential between the anode 623 and the cathode 622. For the purpose of biasing the control grid 621 negatively with respect to the cathode 622, there is provided a resistor 625 which is commonly included in the output circuit 55 of the tube and the energizing circuit for the cathode 622. The anode current source is bypassed for signal frequency currents by a condenser 626. The secondary winding 629 of the transformer 627 is connected to impress the signal voltage developed thereacross upon the input terminals of the loud speaker 136 through a volume control network 141. This network includes three resistors 142, 143 and 144 and an adjustable contact carrying arm 145 so arranged that adjustment of the arm 145 varies the magnitude of the signal voltage impressed upon the input terminals of the loud speaker 136 without substantially changing the value of the resistance 60 connected in shunt with the transformer secondary winding 629. By this arrangement, adjustment of the signal input level to the loud speaker 136 may be achieved, in a well-known manner, without changing the output impedance into which the tube 620 operates, and, hence, with-

out introducing distortion into the reproduced output of the loud speaker 136.

The anti-side-tone impedance network 630 includes, in addition to the transformer 618, a pair of line balancing circuits which are arranged selectively to be operatively included in the network and are individually effective, under different operating conditions, to balance the circuit so that, during operation of the microphone 135, no substantial portion of the developed signal voltage is impressed on the input circuit of the amplifier tube 620. The first of the two balancing networks comprises an adjustable inductance element 631 connected in series with an adjustable resistor 632, and the second network 15 5 similarly comprises an adjustable inductance element 631' connected in series with an adjustable resistor 632'. As shown, the transmitter microphone 135 is included in a substantially closed transmission circuit comprising this microphone, a low impedance condenser 139, and the primary winding 138 of a coupling transformer 137. This transformer is provided with a secondary winding 140, one terminal of which is connected by way of the conductor C146 to the junction point between the two transformer windings 611 and 612 and the other terminal of which is connected by way of the conductor C147 to the junction point between the two transformer windings 613 and 614. The two junction points noted form the conjugate terminals of the anti-side-tone bridge circuit which is effectively formed when the auxiliary substation equipment is included in an established connection. More 20 25 particularly, signal currents traversing the secondary winding 140 of the transformer 137 during operation of the microphone 135 divide at the two junction points noted, portions of the currents traversing a path comprising the two windings 611 and 613 and one of the two balancing circuits, described above, and other portions of the currents traversing the two windings 612 and 614 and the established loop circuit extending to the repeating transformer 500 or the repeating transformer 300. By suitably proportioning the impedance values of the elements respectively included in the two balancing circuits, the currents traversing the windings 613 and 614 are rendered substantially equal in magnitude and opposite in phase at all frequencies within 30 35 the audio range irrespective of which of the two repeating transformers 300 and 500 is included in the established connection. Similarly, when the impedance values of the elements included in the balancing circuits are proportioned in the 40 45 manner indicated, the signal currents respectively traversing the two windings 611 and 612 are rendered substantially equal in magnitude and opposite in phase at all frequencies within the audio range. Thus, during operation of the 50 transmitter microphone 135, the currents traversing the windings 611, 612, 613 and 614 cause substantially equal and opposite signal voltages to be induced in the secondary winding 615, so that substantially no signal energy is delivered 55 60 to the input circuit of the vacuum tube 620. By virtue of this arrangement, suppression of the side tone is achieved.

For the purpose of utilizing the transmitting and receiving means to answer calls incoming to 70 the executive substation and routed by way of the branch path mentioned above, and for the further purpose of permitting the auxiliary transmitting and receiving means selectively to be connected for use in communicating over either of two 75

simultaneously completed connections, each extending to the executive substation, there are provided an answer switch 111, a transfer switch 113, and two control relays R270 and R520. Both 5 of the two relays R270 and R520 are arranged to be energized in response to the operation of the answer switch 111, the first thereof being operative to condition the signal amplifier comprising the tube 620 for operation, and also to prepare an 10 intermediate loop circuit extending between the repeating transformers 300 and 770. Arranged to be serially included in the intermediate loop circuit is an adjustable resistor 306 for conducting direct current and by-passed for signal frequency 15 currents by a condenser 305. The relay R270 conditions the signal amplifier for operation by supplying anode and cathode energizing voltages to the tube 620 over circuits traced hereinafter. In this regard, it is pointed out that the tube 620 20 is of the well-known C-33 type, which type of tube requires only a low anode voltage to provide reasonably good amplification. Hence, the relay energizing source or battery is used to supply anode and screen voltages to this tube. The 25 same source is used to supply energizing current to the cathode 622 of the tube 620, a voltage dropping resistor 624 being serially included in the cathode energizing circuit for the purpose of fixing the resistance of the circuit so that the rated 30 current of the cathode heater traverses the circuit.

The relay R520, which is energized in response to operation of the answer switch 111, and deenergized in response to the subsequent operation of 35 the transfer switch 110, is arranged to transfer the link line C575, C576, leading to the input terminals 643 and 644, from a connection with the winding 50! of the repeating transformer 500 to a connection with the winding 30! of the repeating transformer 300. This relay also functions 40 selectively to include the two balancing circuits, described previously, in the anti-side-tone impedance network 620 in the manner pointed out more in detail hereinafter. In order 45 to remind a user of the executive substation equipment that the answer switch 111 is in its operated or off-normal position, there is provided a signal lamp 126 which is arranged to be energized in response to the operation of the switch 111 to its off-normal position.

For the purpose of preventing an established connection extending to one of the subordinate substations from being reestablished after the usual release operation is performed at the subordinate substation and before the connection is released at the executive substation, there are included in the control apparatus 415 two relays R530 and R540, the first of which is of the slow-to-operate type, and the last-mentioned of which 55 is of the slow-to-release type. More particularly, current for energizing the transmitter microphone 135 is normally supplied to this microphone over a circuit including the winding of R540. When, however, a release operation is 60 performed at a subordinate substation involved in an established connection extending to the executive substation, the relay R540 cooperates with the back bridge relay R510 to cause the operation of the relay R530, and the last-mentioned relay functions to open the circuit for 65 supplying energizing current to the transmitter microphone 135 and to maintain this circuit open so long as the connection is not released at the executive substation.

Referring now more particularly to the opera-

tion of the switching equipment to establish a connection to one of the substations on a call initiated at the executive substation and assuming that the substation A is being called, the call is initiated by operating the calling switch 109 to 5 the particular off-normal position corresponding to the called substation. More particularly, if the substation A is being called, the key switch 100 is operated from its normal position to its lower off-normal position to close the springs of 10 the three sets 114, 115 and 116. As indicated above, three of the coding relays illustrated in Fig. 2 respond to the operation of any one of the key switches to an off-normal position to provide a marking path for marking the particular called 15 line in the contact level 311 of the rotary switch 310. In the case under consideration, when the springs 114, 115 and 116 are closed, circuits are completed for energizing the three relays R200, 20 R210 and R220, which circuits commonly include the winding of the start relay R450. The operating circuits for the three relays noted may be considered as a single circuit extending from battery at the lower terminal of the winding of R450 by way of this winding to C293, where it 25 divides; one branch extending by way of the winding of R220, C132 and the springs 114 to the grounded conductor C127; a second branch extending by way of R210, C133 and the springs 116 to the grounded conductor C127; and the third 30 branch extending by way of R200, C134 and the springs 115 to the grounded conductor C127. When energized over the above-traced circuits, the four relays R200, R210, R220 and R450 operate and the first three thereof function to complete a 35 marking path identifying the line 322 as the line being called. This marking path extends from ground at RA201 by way of RA211, RA221, and C277 to the twenty-fifth contact of the contact set 311. Due to the above-described arrangement 40 of the coding relays, none of the other marking paths individually corresponding to the other lines directly accessible to the special equipment are completed.

As a further example of the manner in which 45 the coding relays operate in response to selective operation of the calling switches, it is pointed out that if the switch 100 is operated to close the contact springs 112, 113 and 117 a series-parallel circuit is completed for energizing the three 50 coding relays R200, R210 and R230, and the start relay R450. In this case the two relays R200 and R210 are energized over circuits substantially similar to the branch circuits traced above and the relay R230 is energized over a branch circuit extending by way of C293, the winding of 55 R230, C131 and the contact spring 117 to the grounded conductor C127. When the three relays R200, R210 and R230 operate, a marking path is completed for applying ground to the twenty-fourth contact of the set 311, this path 60 extending from ground at RA201 by way of RA211, RA231 and C278 to the twenty-fourth of the set 311.

Again, if the tenth calling switch 109 is operated 65 to its lower off-normal position, the springs 121, 122 and 123 are closed to complete a series-parallel circuit for energizing the three relays R200, R240 and R260 in series with the relay R450. In this case the relay R200 is energized 70 over a branch circuit extending by way of C134 and the springs 123 to the grounded conductor C127; the relay R240 is energized over a branch circuit extending by way of C130 and the springs 122 to the grounded conductor C127; and the 75

relay R260 is energized over a branch circuit extending by way of C128 and the springs 121 to the grounded conductor C121. Upon operating, the three relays complete a path extending from ground at RA261 and by way of RA246, RA203 and C279 for impressing marking ground on the nineteenth contact of the contact set 311. It will be apparent from the foregoing description that by selectively operating the calling switches, the coding relays may be caused to operate in different combinations of three, thereby selectively to complete the twenty marking paths extending to the respective contacts of the contact set 311.

In any case when three of the coding relays are energized the start relay R450 is also energized and, upon operating, completes, at RA453, paths commonly including the grounded armature RA559 and C470 for applying ground to the ringing apparatus start conductor C408, thereby to initiate the operation of the ringing apparatus in the usual manner. At RA454, the relay R450 applies ground to the amplifier start conductor C294, thereby to condition the amplifier comprising the tube 620 for operation. More particularly, operation of the relay R450 results in the connection of the positive terminal of the current supply source or battery to C294, so that anode potential is impressed through the primary winding 628 of the output transformer 627 on the anode 623 of the vacuum tube 620. Operation of the relay R450 also results in the completion of a circuit for energizing the cathode 622 of the tube 620, this circuit extending from the grounded positive terminal of the supply battery at RA454 by way of C294, the voltage dropping resistor 624, the cathode 622 and the biasing resistor 625 to the negative terminal of battery. It will be noted that positive screen potential is applied to the screen electrode of the tube 620 directly from the positive terminal of the supply battery over the path including the conductor C294.

At RA451, the relay R450 completes a circuit for energizing the slow-to-operate relay R430, this circuit extending from ground at RA451 by way of RA422, RC423, C336, the armature 319', C331 and the winding of R430 to battery. The relay R430 operates, after an interval, and, at RA431, prepares a circuit, traced hereinafter, for energizing the relay R420 when the wipers of the rotary switch 310 are stepped to the position corresponding to the selected called line 701. At RA435, the relay R430 completes a circuit for energizing R440, this circuit extending from ground at RA451 by way of RA422, RC423, C336, the armature 319', C331, RA435 and the winding of R440 to battery.

When energized over the circuit just traced, the relay R440 operates to complete, at RA441, a circuit for energizing the motor magnet 319 of the switch 310, this circuit extending from ground at the grounded contact RC427 by way of RA426, RA441, C338, and the winding of the magnet 319 to battery. Upon operating, the magnet 319 steps the wipers 315 to 318, inclusive, of the switch 310 one step and interrupts, at its associated armature 319', the above-traced operating circuits for the two relays R430 and R440. The relay R440 immediately restores to interrupt, at RA441, the operating circuit as traced above for the magnet 319, whereupon this magnet restores its associated armature 319' to recomplete the operating circuits for the two relays R430 and R440, respectively. When

the operating circuit for R440 is again completed, this relay operates to recomplete the above-traced circuit for energizing the magnet 319, causing this magnet to again step the enumerated wipers of the switch 310 a second step and to again interrupt the operating circuits for the two relays R430 and R440. The above-described interaction between the relay R440 and the magnet 319 continues until such time as the wipers of the switch 310 are stepped to the position corresponding to the called line 701, or until the wiper 315 is moved into engagement with the contact marked with ground over the above-traced marking path. During the interaction between the relay R440 and the magnet 319, the relay R430, due to its slow-to-release characteristic, stays operated.

When the wiper 315 of the switch 310 is operated into engagement with its associated twenty-fifth contact, the above-mentioned circuit is completed for energizing the relay R420, this circuit extending from the grounded conductor C271 by way of the twenty-fifth contact of the set 311, the wiper 315, C333, RA 431 and the lower winding of R420 to battery. When its lower winding is energized over the circuit, just traced, the relay R420 immediately operates to interrupt, at RA426 and RC427, the above-traced circuit for energizing the magnet 319, thereby to arrest the interaction between this magnet and the relay R440 and to prevent further movement of the wipers embodied in the rotary switch 310. At RA425, the relay R420 completes a holding circuit for itself, this holding circuit extending from the grounded conductor C333, by way of RA425 and the upper winding of R420 to battery. At RA422 and RC423, the relay R420 interrupts a point in the circuits over which R430 and R440 are being held energized, causing these two relays to restore. At RA422 and RC424, the relay R420 prepares a holding circuit, traced hereinafter, for R560.

As indicated above, the auxiliary switching apparatus shown in Fig. 7 is only operable to extend connections to the executive substation and can not be used to set up communication connections between the other substations. Also, the switching equipment and associated control apparatus shown in Figs. 2 to 5, inclusive, can only be used to forward connections from the executive substation to the other substations. Thus, the provision of apparatus for testing the idle or busy condition of a selected called line is unnecessary.

A short time interval after the switch 310 is operated to the position corresponding to the line 701 or, more particularly, a short time interval after the relay R420 operates, the slow-to-release relay R430 restores to complete, at RA432 and RC434, a circuit for energizing the slow-to-operate control relay R400, this circuit extending from ground at RA451 by way of the winding of R400, RC434, RA432, RA421, C334, the wiper 316 and its associated twenty-fifth contact to battery as impressed upon the control conductor C701 of the line 701 through the lower winding of R710. Shortly following its energization over the circuit just traced, the slow-to-operate relay R400 operates to complete, at RA401, a circuit for energizing the ringing relay R560, this circuit extending from ground at RA451 by way of RA422, RC424, RA401, C463 and the winding of R560 to battery. Upon operating, the relay R560 completes, at RA561, a holding circuit for itself, which circuit extends from ground at RA451.

by way of RA422, RC424, C462, RA567 and the winding of R560 to battery. At RA568, the relay R560, upon operating, applies ground to the control conductor C767 of the called line 701, thereby to complete a circuit for energizing the lower winding of the line relay R710 associated with the called line 701. Specifically, the above-mentioned circuit extends from ground at RA568 by way of C464, RA421, C334, the wiper 316 and its associated twenty-fifth contact, C707 and the lower winding of R710 to battery.

When its lower winding is energized over the circuit just traced, the relay R710 operates to interrupt, at RA711 and RC712, a point in the operating circuit, traced hereinafter, for R730. At RA716 and RC717, the relay R710 opens a point in the operating circuit for R760, thereby to prevent the latter relay from operating when the call is answered. At RA715 and RA716, the relay R710 opens two points in its primary operating circuit, traced hereinafter, and in so doing clears the line 701 of the impedance of its own windings. At RA718, the relay R710 completes an obvious circuit for energizing the slow-to-release relay R790, which latter relay operates to open, at RA791, a point in the common portion of the primary operating circuits for all of the line relays. Thus, calls are prevented from being forwarded to the executive substation at a time when this substation is busy.

It will be noted that, when R560 completes the above-traced circuit for R710, it also completes a path for short-circuiting the winding of R400, causing the last-mentioned relay to restore. At RA401, the relay R400, upon restoring, opens a point in the operating circuit for R560, but the latter relay is held operated over its holding circuit as traced above. At RA565 and its associated grounded contact RC566, the ringing relay R560 prepares a locking circuit, traced herein after, for the slow-acting ring cutoff relay R550. At RA561 and RA562, the relay R560 completes a path for projecting ringing current over the called line 701, thereby to energize the signal device at this substation. Specifically, the path traversed by the ringing current extends from one terminal of the ringing current source, not shown, by way of C405, C467, RA557, RA561, C339, the wiper 318 and its associated twenty-fifth contact, the line conductor C704, the signal device at the called substation, the line conductor C703, the wiper 317, C335, RA563, RA562, RA552, RC553 and the lower winding of R550 to the other terminal of the ringing current source. The resulting operation of the signal device provided at the called substation indicates that this substation is being called. The relay R560 also completes a path for transmitting ringback-tone energy to the input circuit of the signal amplifier tube 620. Specifically, the path of the ring-back-tone current extends from the ungrounded terminal of the ringing current source, not shown, by way of the conductor C405, the condenser 403, C468, RA569, RA558, RA542, RC529', RA528, C576, the transformer windings 612 and 611, the inductance element 631, the resistor 632, C572, RC522, RA521, C574, the transformer windings 613 and 614, C575, RA524, RC525 and the upper half of the winding 501 to the grounded terminal 70 of the busy-tone source at the grounded center tap 502 of the winding 501. This current causes an induced voltage to be developed in the transformer winding 615 which is impressed through the coupling transformer 618 between the input electrodes of the tube 620, and the amplified out-

put energy is delivered through the transformer 627 and the volume control network 141 to the loud speaker 136 for reproduction. The reproduced ring-back-tone signal indicates to the calling party that the desired substation is being rung.

The desired conversational connection is completed when the call is answered at the called substation A. More particularly, when the receiver at the substation A is removed from its hook, a direct current bridge is placed across the line conductors C703 and C704 of the line 701 to complete a circuit substantially similar to that, traced previously and traversed by the ringing current, for energizing the lower winding of the ring cutoff relay R550. When its lower winding is energized, the relay R550 first closes the X contacts associated with RA556, thereby to complete the above-mentioned holding circuit for itself, this circuit extending from ground at RC566 by way of RA565 and the two windings of R559 in series to battery. At RA552 and RA557 and their respective associated resting contacts, the relay R550 opens two points in the above-traced path for projecting ringing current over the selected called line 701 and, in so doing, opens two points in its own operating circuit. At these same armatures and their respective working contacts, the relay R550 extends the called substation loop circuit to the repeating transformer 500, thereby to complete a circuit including this loop circuit for energizing the back bridge or called party answer relay R510. At RA558, the relay R550 opens a point in the above-traced path traversed by the ring-back-tone current and, at RA559, it opens a point in the above-traced path for applying ground to the ringing apparatus start conductor C408.

When the relay R510 operates, it completes, at RA511 and RC513, a circuit for energizing the slow-to-release relay R540, this circuit extending by way of RA532, C571, the transmitter microphone 135, the winding 138, C570 and through the winding of R540 to battery. Current for energizing the transmitter microphone 135 is conducted to the microphone over the circuit just traced. Upon operating, the relay R540 prepares, at RA541, a circuit, traced hereinafter, for energizing R530. At RA542, the relay R540 opens a further point in a path for conducting ring-back-tone current by way of the anti-side-tone impedance network 630 to the input circuit of the amplifier tube 620.

Following the operation of R540, the desired conversational circuit is completely established, talking battery being supplied to the loop extending to the called substation A through the windings of the back bridge relay R510, and talking battery being supplied to the transmitter microphone 135 over the circuit, traced above, for energizing the relay R540. Signal currents incoming to the special substation and traversing the windings 503 and 504 of the repeating transformer 500 cause induced voltages to be developed in the winding 501 coupled to the two windings 503 and 504, whereby signal currents corresponding to the incoming signal currents are caused to flow through the anti-side-tone impedance network 630. More particularly, the path followed by currents traversing the winding 501 may be traced as extending from the lower terminal of this winding by way of RC529', RA528, C576, the two windings 612 and 611, the inductance element 631, the resistor 632, C572, RC522, RA521, C574, the two windings 613 and 614, C575, RA524, RC525 and the upper half of the winding 501 to the grounded terminal 70 of the busy-tone source at the grounded center tap 502 of the winding 501. This current causes an induced voltage to be developed in the transformer winding 615 which is impressed through the coupling transformer 618 between the input electrodes of the tube 620, and the amplified out-

614, C575, RA524, RC525, back to the upper terminal of the winding 501. The resulting induced voltages developed in the winding 615 are impressed through the coupling transformer 618 and the voltage dividing resistor 619 between the input electrodes of the amplifier tube 620, thereby to cause corresponding amplified currents to flow in the output circuit of this tube. Such currents cause induced voltages to be produced in the winding 629 of the output coupling transformer 627, which voltages are impressed through the potentiometer network 141 on the input terminals of the loud speaker 136 for reproduction.

15 Audio frequency currents developed by operation of the microphone 135 are caused to circulate in the closed low impedance transmission circuit comprising the primary winding 138 of the transformer 137 and the condenser 139. Such currents cause corresponding induced voltages to be developed in the secondary winding 140 of the transformer 137 which are impressed by means of the two conductors C146 and C147 between opposite terminals of the anti-side-tone impedance network 630. More particularly, signal currents traversing the winding 140 divide at the terminals of the anti-side-tone impedance network and follow the two paths traced previously, whereby the well-known anti-side-tone effect is realized.

30 The release of the established communication connection is primarily under the control of the calling party. If the called party at the substation A restores his receiver to its hook before the calling key switch 100 is returned to normal, the established called party loop circuit extending to the repeating transformer 500 is interrupted, causing the back bridge relay R510 to restore in the usual manner. Upon restoring, the relay R510 interrupts, at RA511 and RC513, the above-traced circuit for energizing R540 and, at RA511 and RC512, it completes a circuit for energizing the slow-to-operate relay R530, the latter circuit extending by way of RA527, RA541 and the winding of R530 to battery. Upon operating, the relay R530 completes, at RA531, a holding circuit for itself, this circuit extending from ground at RA555 by way of RA531 and the winding of R530 to battery. It is noted that the relay R530, although of the slow-to-operate type, operates to complete its holding circuit before the slow-to-release relay R540 restores to open the operating circuit for R530. At RA532, the relay R530, upon operating, opens a further point in the above-traced operating circuit for R540 and, in so doing, opens a further point in the circuit by way of which energizing current is delivered to the microphone 135. At RA534, the relay R530 applies ground by way of C470 to the start conductor C408, thereby to reinitiate the operation of the ringing apparatus providing this apparatus is not already in operation. At RA533, the relay R530 completes an alternative path for impressing ring-back-tone voltage upon the input circuit of the signal amplifier tube 620, thereby to cause ring-back tone to be reproduced by the loud speaker 136. The ring-back-tone signal produced by operation of the loud speaker 136 indicates to the calling party that the key switch 100 has not been restored to normal.

70 The purpose of providing the relay R530, which operates in response to the release operation performed at the called substation, is that of positively preventing eavesdropping on the part of a called party, following the termination of a conversation between the called party and the

calling executive. Thus, in the absence of this relay and its associated circuits, the called party at the substation A could, after hanging up, again remove his receiver from its hook to recomplete the talking connection, provided the operated key 5 switch 100 was not restored to normal by the calling party. In this regard, it will be appreciated that the back bridge relay R510 would respond to the recompletion of the loop circuit to again complete the circuit for delivering energizing current 10 to the transmitter 135. Obviously, with this connection reestablished, the called party could listen to any conversation being carried on in the office of the executive. With the arrangement illustrated, however, the relay R530, upon operating, 15 is held operated independently of the back bridge relay R510 and, in its operated position, holds interrupted, at RA532, the above-traced path by way of which energizing current is delivered to the transmitter microphone 135. Thus, the channel for transmitting signal currents outgoing from the special substation to the called substation is rendered completely inactive and eavesdropping on the part of a called party is positively prevented. 25

As indicated above, the common control apparatus 415 is released in response to the restoration of the operated key switch 100 to its normal position. When this switch is returned to normal, the above-traced operating circuits 30 for the four relays R200, R210, R220 and R450 are interrupted, causing all of these relays to restore. When the first three of the enumerated four relays restore, the above-traced marking path extending to the twenty-fifth contact of 35 the contact set 311 in the switch 310 is interrupted. When this path is interrupted, the holding circuit for R420 is broken, causing this relay to restore. Thus, the two operated relays R420 and R450 are caused to restore. When the relay 40 R420 restores, it interrupts, at RA422 and RC424, the circuit over which R560 is being held energized. At RA421, the relay R420 opens a point in the above-traced circuit for energizing the line relay R710, causing this line relay and the relay 45 R790 sequentially to restore in the order named, thereby to establish the circuit connections normally prevailing when the apparatus 700 is idle. During the restoration of the relay R560, the contact springs RA563 and RC564 are moved into 50 engagement before the loop circuit extending to the called substation is interrupted, providing the called party has not restored his receiver to its hook. When the enumerated springs are moved into engagement, the condenser 543 is connected 55 through RA561 between the line conductors C339 and C335. This condenser absorbs the voltage transient which occurs when the talking loop is interrupted at RA561 following the restoration of R560 completely to normal and thus prevents the transient from being reproduced as an objectionable "click" by the receiver at the called substation. When R560 falls back, it interrupts, at RA565 and RC566, a point in the holding circuit for the ring cutoff relay R550, whereby the last-mentioned relay is caused to restore. The relay 60 R560 also opens at RA551 a point in the path connecting the condenser 543 between the link line conductors C335 and C339. Upon restoring, the relay R550 opens, at RA555, a point in the holding circuit for R530. If R530 is operated, it restores to interrupt, at RA533, a point in the above-mentioned alternative path for delivering ring-back-tone energy to the signal amplifier tube 620. At RA534, the relay R530 removes multiple 75

ground from C470. Following the restoration of R530, the common control apparatus 415 is entirely released.

From the foregoing description, it will be apparent that connections may be routed from the executive substation by way of the switch 310 to any one of the various substation lines of the system by selectively operating the calling keys illustrated in Fig. 1. As a further example, it is briefly pointed out that, if the calling key 100 is operated to its upper off-normal position to cause the operation of the three coding relays R200, R210 and R230, a marking path extending to the twenty-fourth contact of the set 311 embodied in the switch 310 is completed which identifies the line 702 as the called line. The manner in which the switch 310, the control apparatus 415, and the line relay R720, associated with the called line 702, respond and forward the connection to the line 702 is exactly the same as that just described with reference to the connection extended to the line 701.

As indicated previously, the apparatus shown in Fig. 7 is only operative to extend a connection from a calling one of the lines 701, 702, etc., to the executive sub-station. A connection may be routed by way of this apparatus to the executive substation only at a time when the executive substation is idle. If, for example, a person at the substation B initiates a call to the executive substation by lifting the hand set at this substation from its supporting hook or cradle, the hook or cradle switch operates to connect a direct current bridge between the line conductors C705 and C706, thus completing the primary operating circuit for the relay R720. Specifically, this circuit extends from ground at RC721 by way of RA726, C705, the bridge connected between C705 and C706 at the calling substation, C706, RA725, the upper winding of R720 and RA791 to battery. When its upper winding is energized over this circuit, the relay R720 only partially operates to complete at the X contacts associated with RA724 a circuit for energizing the slow-to-operate control relay R740. The last-mentioned circuit extends from ground at RC722 by way of RA721, RA724, and the winding of R740 to battery. At the X contacts associated with RA724', the relay R720 prepares a point in its secondary operating circuit, traced hereinafter. Upon operating, the relay R740 attracts its associated armatures RA741 and RA742 into engagement with their respective associated working contacts, thereby to extend the calling loop to the repeating transformer 770 and to complete a circuit for energizing the common control relay R760. The circuit for energizing R760 may be traced as extending from ground by way of the winding 772, C782, RA742, C785, the bridge across C706 and C705 at the calling substation, C705, RA741, C781, the winding 771 and the winding of R760 to battery. When energized over this circuit, the relay R760 operates to complete, at RA761, the above-mentioned secondary operating circuit for R720, which circuit extends from ground by way of RA761, RA724' and the lower winding of R720 to battery. It will be noted that the relay R760 also prepares the secondary operating circuits for the respective other line relays. Thus, at RA764, the relay R760 prepares a secondary operating circuit for R710. The secondary operating circuit for the relay R710 is, however, open at RA714'.

When the secondary operating circuit for the relay R710 is completed, this relay completes

its operation to interrupt, at RA725 and RA726, two points in its primary operating circuit as traced above. At RA721 and RC723, the relay R720 completes a holding circuit for R740, this circuit extending from ground by way of RA762, RC723, RA721, RA724, and the winding of R740 to battery. At RA728, the relay R720, upon fully operating, completes an obvious circuit for energizing the slow-to-release relay, R790, which latter relay operates to interrupt, at RA791, a point 10 in the common portion of the primary operating circuits for the line relays respectively associated with the various substation lines, thereby to prevent any further ones of the line relays from being energized in response to the initiation of calls 15 on the lines respectively associated therewith.

At RA766 and its associated working contact, the relay R760, upon operating, completes a path extending from ground at RC756 for applying ground to the ringing apparatus start conductor 20 C498, thereby to initiate the operation of this apparatus in the usual manner. At RA765 and its associated working contact, the relay R760 completes a circuit for energizing the signal device 160 provided at the executive substation, this circuit extending from one terminal of the ringing current source, not shown, by way of C405, RA785, RA781, C786, the signal device 160, C787, RA752 and through the winding of R750 to the opposite terminal of the ringing current source. 30 A portion of the ringing current is by-passed through the condenser 757 and the winding 773, thereby to cause a ring-back-tone voltage to be impressed upon the loop extending to the calling substation B. The resulting operation of the receiver at the calling substation indicates that the executive substation is being rung.

To answer the call, the answer switch 111 is operated to its off-normal position to close the springs 125 and thereby complete a circuit for 40 energizing the control relay R520. The circuit noted extends from the grounded conductor C127 by way of the springs 125, the springs 124, C152, and the winding of R520 to battery. At the springs 125, a circuit is also completed for energizing the signal lamp 126 in series with the winding of R270, this circuit extending from the grounded conductor C127 by way of the springs 125, the signal lamp 126, C127' and the winding of R270 to battery. When energized over the 50 above-traced circuit, the relay R270 operates and the signal lamp 123 is illuminated to indicate that the answer switch 111 occupies its off-normal position. The relay R270, upon operating, completes, at RA272, a path for applying ground 55 to the amplifier start conductor C294, whereby the signal amplifier comprising the vacuum tube 620 is conditioned for operation in the manner described previously. At RA271, the relay R270 completes a direct current bridging path between 60, the line conductors C785 and C787 of the link line 785, which path includes the two windings 303 and 304 of the repeating transformer 300. More particularly, the bridging path noted extends from the line conductor C787 by way of the winding 304, the resistor 306, C298, RA271, C299 and the winding 303 to the opposite line conductor C786.

When the above-traced path between the conductors of the line 785 is completed, the slow-to-operate relay R750 is energized by direct current and operates. The operating circuit for R750 extends from ground by way of the ringing current source, not shown, C405, RA765, RA751, C786, the above-traced bridging path, C787, RA752 and 75-

the winding of R750 to battery. Upon operating, the relay R750 completes, at RA751 and RA752 and their respective associated working contacts, a holding circuit for itself, which circuit includes the two windings 773 and 774, and the closed loop extending to the transformer 300. At RA751' and RA752', the relay R750 opens two points in its operating circuit and in so doing interrupts the circuit for energizing the signal device 163 and the circuit for impressing ring-back-tone energy on the loop extending to the calling substation. At RA753, the relay R750 prepares an alternative path for projecting ringing current over the line 785 and, at RA754, it 10 interrupts a point in the path for applying ground to the ringing apparatus start conductor C408. At RA755, the relay R750 prepares an alternative path for applying ground to the start conductor C408. Following the operation of 15 R750, the talking loop is extended to the repeating transformer 300.

As indicated above, the relay R520 is energized in response to the operation of the answer switch 111 to its off-normal position. When energized, 20 this relay operates to complete, at RA528, the above-traced circuit for energizing R540 and by way of which energizing current is delivered to the transmitter microphone 135. At RA527, the relay R520 opens a point in the above-traced operating circuit for R530, thereby to prevent the last-mentioned relay from operating in response to the operation of R540. At RA524 and RA528 and their respective associated resting contacts RC525 and RC529', the relay R520 disconnects 25 the line conductors C575 and C576 from the winding 501 of the repeating coil 500, and, at these same armatures and their respective associated working contacts RC526 and RC529, connects the line conductors C575 and C576 by way 30 of the link line conductors C296 and C297, respectively, to the opposite terminals of the repeating transformer winding 301. Thus, the repeating transformer 300 is incorporated in the newly established talking connection in lieu of 35 the repeating transformer 500, which latter transformer is used only on calls originated at the special substation and routed by way of the switch 310. Since the impedance characteristics of the line apparatus associated with the repeating transformers 500 and 300 may be different, it is desirable to provide alternative line 40 balancing circuits arranged alternatively to be included in the anti-side-tone impedance network 630. As described above, with the relay R520 de-energized, the line balancing circuit comprising 45 the inductance element 631 and the resistor 632 is operatively included in the anti-side-tone impedance network 630. When, however, the relay R520 operates, it substitutes the other balancing circuit, namely, that comprising the inductance element 631' and the resistor 632', for the first- 50 mentioned balancing circuit in the anti-side-tone impedance network. This is accomplished through the operation of R520 to disconnect, at RA521, the conductor C574, extending to the upper terminal of the winding 613, from the conductor C572 and to connect this conductor to the conductor C573. It will be understood that the line balancing circuit comprising the inductance element 631' and the resistor 632' is adjusted to 55 have a frequency-impedance characteristic substantially matching that of the equivalent impedance of the repeating transformer 300 and the line impedances associated therewith as determined at the line terminals 643 and 644 of the 60

impedance network 630. Similarly, the line balancing circuit comprising the inductance element 631 and the resistor 632 is adjusted to have a frequency-impedance characteristic substantially the same as that of the equivalent impedance of the repeating transformer 500 and the line impedances associated therewith as determined at the line terminals 643 and 644 of the network 630.

Following the operation of R520, the desired conversational connection is fully completed. 10 After the conversation is terminated the connection is only released when the answer switch 111 is restored to normal and the calling party hangs up. When the calling party hangs up, the bridge across the line conductors C705 and C706 is interrupted to open the circuit over which R760 is being held energized. When R760 restores it opens at RA761 and RA762, respectively, the holding circuits for R720 and R740 causing the two last-mentioned relays to restore. 15 Upon restoring, the relay R720 opens the operating circuit for R790, which latter relay restores after an interval. When R790 restores it reprepares, at RA791, the operating circuits for all 20 of the line relays. It is noted that the two relays R720 and R740 are connected and arranged to restore before the relay R790 falls back. Thus, the relay R720 has ample time to restore to open, at RA724, its secondary operating circuit and, at RA724, the holding circuit for R740 before 25 the relay R760 can reoperate in response to a waiting call to recomplete the two last-mentioned circuits. By this arrangement the possibility of two substation lines being simultaneously and inadvertently connected to the link line 30 35 40 45 50 55 60 65 70 75 80 85 90 95 100 105 110 115 120 125 130 135 and receiving means are entirely disconnected from the link line C296, C297. When the direct current bridge between the conductors of the line 785 is interrupted, the relay R750 is deenergized and restores. Upon restoring, this relay interrupts, at RA753, the above-traced path for projecting ringing current over the line 785, and, at RA755, it interrupts the above-mentioned path for applying ground to the start conductor 10 C408.

If the called party at the executive substation restores the answer switch 111 to normal before the connection is cleared out at the calling substation B, the relays R520, R540, R270 and R750 are caused to restore in the manner just described. Under this condition the relay R760 is still operated, so that the relay R750, upon restoring, recompletes the above-traced path for applying ground to the start conductor C408 and the above-traced circuit for again energizing the signal device 160 provided at the executive substation. When thereafter the calling party hangs up the relays R760, R740, R720 and R790 are caused to restore in the order named and 25 in the manner described previously. The relay R760, upon restoring removes ground from the start conductor C408 and opens, at RA765, the circuit for energizing the signal device 160. Thus, the connection is entirely released.

30 The mode of operation of the relays R760 and R790, common to the lines, and of the line and control relays individual to another of the lines to extend a connection to the executive substation is substantially the same as that just 35 described and will readily be apparent from the preceding description.

As indicated in the introductory portion of the specification, a party at the executive substation may utilize the automatic switching apparatus 40 including the switch 310 to route a connection to one of the substation lines during the course of a conversation over an established connection extending to another of the substation lines, assuming of course that the first connection is 45 routed by way of the apparatus 700. For example, if a party at the executive substation answers the above-described call initiated at the substation B and desires to secure information from a party having an office in which the substation A is located, the direct call to the substation A is initiated by first operating the calling switch 100 to the lower off-normal position in the manner described above. The coding relays R200, R210 and R220, the common equipment 415 and the rotary switch 310 respond to the operation of the switch 100 to its off-normal position by performing the previously described functions, whereby a connection is completed between the repeating transformer 560 and the called line 701. In this regard it will be recalled 50 that the three relays R270, R520 and R540 are operated. Hence, the amplifier comprising the vacuum tube 620 is conditioned for operation and the line conductors C575 and C576 incoming to 55 the anti-side-tone impedance network 630 are connected through to the repeating coil 300. The operated condition of the three relays R270, R520 and R540 in no way interferes with the operation of the other relays included in the common control apparatus 415 to cause the connection to the desired line 701 to be established. 60 When the transfer switch 110 is operated to its off-normal position, following operation of the calling switch 100 to the off-normal position corresponding to the called line 701, the operating 65

circuit for the relay R520 is interrupted at the springs 124, causing this relay to restore. When the relay R520 falls back, it disconnects the line conductors C575 and C576 from across the terminals of the transformer winding 301 and connects these line conductors to the respective terminals of the transformer winding 501, thereby operatively to include the transmitting and receiving means comprising the loud speaker 136 and the transmitter microphone 135 in the established connection extending to the called substation line 701. The relay R520, upon restoring, also disconnects the conductor C574 from the conductor C573 and connects it to the conductor C572, thus substituting the line balancing circuit comprising the inductance element 631 and the resistor 632 for the balancing circuit comprising the inductance element 631' and the resistor 632' in the anti-side-tone impedance network 630. With the relay R520 in its restored position, the original circuit for supplying energizing current to the microphone 135 and for holding R540 operated, is interrupted at RA523'. At this time, however, the back bridge relay R510 is in its operated position so that a multiple circuit extending from ground at RA511 and by way of RC513 and RA532 is completed for maintaining R540 operated and for supplying energizing current to the microphone 135.

It will be noted that to effect the transfer operation just described the transfer switch 110 is operated to its off-normal position without restoring the answer switch 111 to its normal position. So long as the last-mentioned switch is 35 retained in its off-normal position, the above-traced circuit by way of which the relay R270 is energized is held completed and, so long as R270 is energized and remains in its operated position, the loop circuit extending to the transformer 770 and including the line 785 is maintained completed at RA271. After the two connections extending, respectively, to the substations A and B are established, the party at the executive substation may, by operating the transfer switch 110 between its normal and off-normal positions, converse over either of the two connections at will. Thus, if the party at the executive substation, after conversing with the called party at the substation A, desires to again converse with the party at the substation B, he may do so by returning the transfer switch 110 to its normal position to recomplete the above-traced operating circuit for R520. It will be apparent, in view of the foregoing description, that when R520 reoperates it substitutes the balancing circuit comprising the inductance element 631' and the resistor 632' for the balancing circuit 631, 632 in the anti-side-tone impedance network, disconnects the line conductors C575 and C576 from the transformer winding 501, and reconnects the line conductors C575 and C576 to the terminals of the repeating transformer winding 301.

In order to release the two established connections, it is only necessary for the two parties at the substations A and B to hang up and for the party at the executive substation to restore the operated switches 100 and 111 to normal. When the switch 100 is returned to its normal position, the three operated coding relays R200, R210 and R220 are caused to restore, together with the start relay R450. Following the restoration of these four relays, the remaining operated relays embodied in the common control appara- 70 75 80 85 90 95

tus 415 are caused sequentially to restore in the manner described in detail in a preceding portion of the specification. Also, when the answer switch 111 is returned to its normal position, the three operated relays R520, R540 and R270 are deenergized and restore in the manner described previously. When the two parties at the substations A and B, respectively, hang up the apparatus 700 is restored to normal in the manner described previously.

With the arrangement illustrated it is not possible for a connection to be extended by way of the apparatus 700 to the executive substation at a time when the executive substation is busy. This is true for the reason that in any case when a connection is established, the relay R790 is operated and holds open, at RA791, a point in the common portion of the respective primary operating circuits for the line relays R710, R720, etc., and with their primary operating circuits open the line relays cannot be energized in response to the initiation of calls on their respective associated lines.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In a telephone system, a substation, a plurality of telephone lines, means comprising automatic switching equipment controllable from said substation for establishing connections between said substation and said lines on calls initiated at said substation, and auxiliary automatic switching apparatus associated with said lines, said auxiliary switching apparatus being so connected and arranged that a talking connection is extended from a calling one of said lines to said substation over a route from which said automatic switching equipment is excluded in response to the initiation of a call on said one line and that connections can only be routed by way thereof to said substation.

2. In a telephone system, a first substation, a plurality of substation lines each including a pair of line conductors, substations individually associated with said lines and each including means for connecting a bridge across the line conductors of the associated line, means comprising automatic switching equipment controllable from said first substation for establishing connections between said first substation and said lines on calls initiated at said first substation, and auxiliary switching apparatus associated with said lines, said auxiliary switching apparatus being so connected and arranged that a connection is extended from a calling one of said lines to said first substation in response to the connection of a bridge across the conductors of said one line and that connections can only be routed by way thereof to said first substation.

3. In a telephone system, a first substation, a plurality of substation lines each including a pair of line conductors, substations individually associated with said lines and each including means for connecting a bridge across the line conductors of the associated line, means comprising automatic switching equipment controllable from said first substation for establishing connections between said first substation and said lines on calls initiated at said first substation, and auxiliary switching apparatus associ-

ated with said lines, said auxiliary switching apparatus including a control relay commonly associated with said lines and at least one relay individual to each line and being so connected and arranged that connections can only be routed by way thereof to said first substation, said control relay and the relay individual to a calling one of said lines being operative in response to the connection of a bridge across the conductors of said one line to extend a connection from said one line to said first substation.

4. In a telephone system, a first substation, a plurality of substation lines each including a pair of line conductors, substations individually associated with said lines and each including means for connecting a bridge across the line conductors of the associated line, means comprising automatic switching equipment controllable from said first substation for establishing connections between said first substation and said lines on calls initiated at said first substation, auxiliary switching apparatus associated with said lines, said auxiliary switching apparatus including a relay common to said lines and at least one relay individual to each line and being so connected and arranged that connections can only be routed by way thereof to said first substation, a signal device at said first substation, a normally incomplete circuit for energizing said signal device, said common relay and the relay individual to a calling one of said lines being operative in response to the connection of a bridge across the conductors of said one line to extend a connection from said one line to said first substation, and means responsive to the operation of said common relay for completing said circuit.

5. In a telephone system, a substation, a plurality of telephone lines, means comprising automatic switching equipment controllable from said substation for establishing connections between said substation and said lines on calls initiated at said substation, auxiliary switching apparatus associated with said lines, said auxiliary switching apparatus being so connected and arranged that a connection is extended from a calling one of said lines to said substation in response to the initiation of a call on said one line and that connections can only be routed by way thereof to said substation, and means operative in response to the initiation of a call on one of said lines for rendering said auxiliary switching apparatus ineffective to extend a connection from any of the other lines to said substation.

6. In a telephone system, a first substation, a plurality of substation lines each including a pair of line conductors, substations individually associated with said lines and each including means for connecting a bridge across the line conductors of the associated line, means comprising automatic switching equipment controllable from said first substation for establishing connections between said first substation and said lines on calls initiated at said first substation, auxiliary switching apparatus associated with said lines, said auxiliary switching apparatus being so connected and arranged that a connection is extended from a calling one of said lines to said first substation in response to the connection of a bridge across the conductors of said one line and that connections can only be routed by way thereof to said first substation, and means operative in response to the connection of a bridge across the conductors of said one line for preventing said auxiliary switch-

ing apparatus from operating to extend a connection from a second line to said first substation in response to the connection of a bridge across the conductors of said second line.

- 5 7. In a telephone system, a first substation, a plurality of substation lines each including a pair of line conductors, substations individually associated with said lines and each including means for connecting a bridge across the line 10 conductors of the associated line, means comprising automatic switching equipment controllable from said first substation for establishing connections between said first substation and said lines on calls initiated at said first substation, auxiliary switching apparatus associated with said lines, said auxiliary switching apparatus including a control relay commonly associated with said lines and at least one relay individual to each line and being so connected and arranged 15 that connections can only be routed by way thereof to said first substation, said control relay and the relay individual to a calling one of said lines being operative in response to the connection of a bridge across the conductors of 20 said one line to extend a connection from said one line to said first substation, and means operative in response to the operation of the relay individual to said one line for preventing any of the other similar relays from operating 25 30 in response to the connection of bridges across the conductors of the respective associated lines.
8. In a telephone system, a first substation, a plurality of substation lines each including a pair of line conductors, substations individually associated with said lines and each including means for connecting a bridge across the line conductors of the associated line, means comprising automatic switching equipment controllable from said first substation for establishing 35 40 connections between said first substation and said lines on calls initiated at said first substation, auxiliary switching apparatus associated with said lines, said auxiliary switching apparatus including a relay common to said lines and at least one relay individual to each line and being so connected and arranged that connections can only be routed by way thereof to said first substation, a signal device at said first substation, a normally incomplete circuit for energizing said 45 50 signal device, said common relay and the relay individual to a calling one of said lines being operative in response to the connection of a bridge across the conductors of said one line to extend a connection from said one line to said first substation, means responsive to the operation of said common relay for completing said circuit, and means operative in response to the operation of the relay individual to said one line for preventing any of the other similar relays 55 60 from operating in response to the connection of bridges across the conductors of the respective associated lines.
9. In a telephone system, a substation, a plurality of telephone lines, an automatic switch having access to said lines, a plurality of manually operable calling switches at said substation, said calling switches individually corresponding to said lines, means operative in response to the operation of any one of said calling switches 65 70 for causing said automatic switch to select the called line corresponding to said one calling switch and for establishing a connection between the called line and said substation, a branch path common to said lines and arranged 75 to be included only in connections routed by way

of said lines to said substation, said branch path including a link line, line relays individually associated with said telephone lines and individually operative in response to the initiation of calls on the respective associated lines, and control relays individually associated with said telephone lines and said line relays, each of said control relays including contacts for connecting the associated line to said link line, thereby to extend a connection from the associated line to said substation, and having an operating circuit arranged to be completed in response to operation of the associated line relay.

10. In a telephone system, a substation, a plurality of telephone lines, an automatic switch 15 having access to said lines, a plurality of manually operable calling switches at said substation, said calling switches individually corresponding to said lines, means operative in response to the operation of any one of said calling switches for 20 causing said automatic switch to select the called line corresponding to said one calling switch and for establishing a connection between the called line and said substation, a branch path common to said lines and arranged to be included only 25 in connections routed by way of said lines to said substation, said branch path including a link line, line relays individually associated with said telephone lines and individually operative in response to the initiation of calls on the respective 30 associated lines, control relays individually associated with said telephone lines and said line relays, each of said control relays including contacts for connecting the associated line to said link line, thereby to extend a connection from 35 the associated line to said substation, and having an operating circuit arranged to be completed in response to operation of the associated line relay, and means operative in response to the initiation of a call on any one of said telephone 40 lines for preventing the line relays, other than the line relay associated with the calling line, from operating in response to calls initiated on the respective associated lines.

11. In a telephone system, a substation, a plurality of telephone lines, an automatic switch having access to said lines, a plurality of manually operable calling switches at said substation, said calling switches individually corresponding to said lines, means operative in response to the 45 operation of any one of said calling switches for causing said automatic switch to select the called line corresponding to said one calling switch and for establishing a connection between the called line and said substation, a branch path common to said lines and arranged to be included only 50 in connections routed by way of said lines to said substation, said branch path including a link line, line relays individually associated with said telephone lines and individually operative in response to the initiation of calls on the respective 55 associated lines, control relays individually associated with said telephone lines and said line relays, each of said control relays including contacts for connecting the associated line to said link line, thereby to extend a connection from the associated line to said substation, and having an operating circuit arranged to be completed in response to operation of the associated 60 line relay, and means operative in response to the operation of any one of said line relays for preventing the other line relays from operating in response to calls initiated on the respective associated lines.

12. In a telephone system, a substation, a plu- 75

rality of telephone lines, an automatic switch having access to said lines, a plurality of manually operable calling switches at said substation, said calling switches individually corresponding to said lines, means operative in response to the operation of any one of said calling switches for causing said automatic switch to select the called line corresponding to said one calling switch and for establishing a connection between the called line and said substation, a branch path common to said lines and arranged to be included only in connections routed by way of said lines to said substation, said branch path including a link line, line relays individually associated with said telephone lines and individually operative in response to the initiation of calls on the respective associated lines, control relays individually associated with said telephone lines and said line relays, each of said control relays including contacts for connecting the associated line to said link line, thereby to extend a connection from the associated line to said substation, and having an operating circuit arranged to be completed in response to operation of the associated line relay, a signal device at said substation, a normally incomplete circuit for energizing said signal device, and means responsive to the operation of any one of said line relays for completing said circuit.

13. In a telephone system, a substation, a plurality of telephone lines, an automatic switch having access to said lines, a plurality of manually operable calling switches at said substation, said calling switches individually corresponding to said lines, means operative in response to the operation of any one of said calling switches for causing said automatic switch to select the called line corresponding to said one calling switch and for establishing a connection between the called line and said substation, a branch path common to said lines and arranged to be included only in connections routed by way of said lines to said substation, said branch path including a link line, line relays individually associated with said telephone lines and individually operative in response to the initiation of calls on the respective associated lines, control relays individually associated with said telephone lines and said line relays, each of said control relays including contacts for connecting the associated line to said link line, thereby to extend a connection from the associated line to said substation, and having an operating circuit arranged to be completed in response to operation of the associated line relay, a signal device at said substation, a normally incomplete circuit for energizing said signal device, and means responsive to the operation of any one of said line relays for completing said circuit, and means operative in response to the operation of any one of said line relays for preventing the other line relays from operating in response to calls initiated on the respective associated lines.

14. In a telephone system, a first substation, a plurality of substation lines each including a pair of line conductors, substations individually associated with said lines and each including means for connecting a bridge across the conductors of the associated line, automatic switching equipment controllable from said first substation for establishing connections between said first substation and said lines on calls initiated at said first substation, a branch path common to said lines and arranged to be included in connections routed by way of said lines to said substation, said branch path including a link line, line relays individually associated with said lines,

control relays individually associated with said lines and said line relays, each of said control relays including contacts for connecting the associated line to said link line, thereby to extend a connection from the associated line to said first substation, an additional relay common to said lines, each of said line relays having an operating circuit including the line conductors of the associated line and arranged to be completed in response to the connection of a bridge across the line conductors of the associated line, operating and holding circuits for each of said control relays, means responsive to the operation of one of said line relays for completing the operating circuit of the one control relay associated with said one line relay, said additional relay having an operating circuit arranged to be completed in response to the operation of any one of said control relays and including the line conductors of any calling one of said lines, holding circuits for each of said line relays, means responsive to the operation of said additional relay for completing the holding circuit for said one control relay and said one line relay, and means responsive to the operation of said line relay for interrupting the operating circuits for all of the other line relays.

15. In a telephone system, a first substation, a plurality of substation lines each including a pair of line conductors, substations individually associated with said lines and each including means for connecting a bridge across the conductors of the associated line, automatic switching equipment controllable from said first substation for establishing connections between said first substation and said lines on calls initiated at said first substation, a branch path common to said lines and arranged to be included in connections routed by way of said lines to said substation, said branch path including a link line, line relays individually associated with said lines, control relays individually associated with said lines and said line relays, each of said control relays including contacts for connecting the associated line to said link line, thereby to extend a connection from the associated line to said first substation, an additional relay common to said lines, each of said line relays having a primary operating circuit including the conductors of the associated line and being partially operative in response to the completion of its primary operating circuit, each of said primary operating circuits being arranged to be completed in response to the connection of a bridge across the conductors of the associated line, secondary operating circuits for said line relays, operating and holding circuits for each of said control relays, said additional relay having an operating circuit including the conductors of any calling one of said lines, means responsive to the partial operation of one of said line relays for completing the operating circuit for the associated control relay, means responsive to the operation of said associated control relay for completing the operating circuit for said additional relay, means responsive to the operation of said additional relay for completing the secondary operating circuit for said one line relay, thereby to cause said one line relay to complete its operation, means responsive to the last-mentioned operation of said one line relay for completing the holding circuit for said associated control relay, and means responsive to the last-mentioned operation of said one line relay for interrupting

the primary operating circuits for all of said line relays.

ROSWELL HARRY HERRICK.
